Alexander Kress
ATTORNEY.

UNITED STATES PATENT OFFICE.

JOHN BARTHA, OF CLINTON, MASSACHUSETTS.

LEVEL.

1,153,012.

Specification of Letters Patent. Patented Sept. 7, 1915.

Application filed November 17, 1914. Serial No. 872,577.

To all whom it may concern:

Be it known that I, JOHN BARTHA, a subject of the King of Hungary, and resident of Clinton, in the county of Worcester and State of Massachusetts, have invented new and useful Improvements in Levels, of which the following is a specification.

My invention relates to levels and has as its principal object to provide an instrument of this kind which, instead of having two separate indicators for horizontal and for perpendicular surfaces, has only one suitable for both.

A further object of my invention is to provide an instrument of the character described which not only indicates whether a surface is horizontal or perpendicular or not, but also how many degrees it deviates from either.

Still another object of my invention is to provide an instrument of the character described that can be used on either side.

With the foregoing and other objects in view, the invention consists of a novel construction, combination and arrangement of parts as hereinafter more specifically described and illustrated in the accompanying drawings, wherein is shown an embodiment of the invention, but it is to be understood that changes, variations and modifications can be resorted to which come within the scope of the claim hereunto appended.

In the accompanying drawing: Figure 1 is a front view of the instrument with parts broken away and some hidden parts shown in dotted lines. Fig. 2 is a top view of the same. Fig. 3 is a section on the line 3—3, Fig. 1, looking in the direction of the arrows.

Similar reference characters are applied to similar parts throughout the different views.

Referring more particularly to the drawing, 4 is a level stock, having in its longitudinal center a circular hole which divides it into two separate pieces, the same being secured together on the top and bottom edges by metal plates 5 and 6, respectively, each being provided at its longitudinal center with an oval opening or slot 7. The edges of the circular hole made in the level stock are beveled on each side and a concave groove is formed in the center of the edge, preferably lined with a metal ring 15. An

annular glass tube 8 is inserted into the hole made in the level stock, its outer circumference being partly embraced by the metal ring 15. The glass tube has a projection 9 radially verging inward, formed theron, through which it may be filled with liquid and then closed by means of a stopper 10. An air bubble 11 is left in the tube for obvious purposes.

Within the tube 8 is provided a disk shaped member 13 having a recess formed in it at one part of its circumference accommodating the projection 9. On each side of the disk shaped member 13 are provided metal coverings 12 having a circular part lying on the side surface of the disk shaped member 13, but of a somewhat larger diameter than the latter so as to reach close to the glass tube and then bent downwardly and inwardly, following the plane of the inner periphery of the glass tube and lying closely against it. The edges of the coverings 12 meet at the central line of the circumferential edge of the disk-shaped member 13.

Brackets 14 secured with one end to the level stock and with the other end to the disk shaped member 13 through the metal coverings 12, hold the elements of this construction securely in place. The top surfaces of the coverings 12 are provided with graduations from 1 to 90° contiguously to the glass tube 8 which graduations may be continued over the glass tube itself as shown at 16.

In assembling the device, the two separate parts of the level stock are placed so as to embrace one end each of the glass tube and then united by the metal plates 5 and 6. The disk shaped member 13 is then placed within the glass tube and the coverings 12 applied to it on either side.

Having thus described my invention, what I claim is:

The combination with a level-body having a circular hole in its longitudinal center throughout its thickness, from its top edge to its bottom edge, of an annular transparent tube containing a fluid and an air-bubble formed therein, said tube fitting into a concave groove formed in the inner edges of said circular slot, a disk shaped member provided with graduations on both sides

filling out the space encompassed by said annular tube, brackets connecting said disk-shaped member to said level-body so as to maintain all the said elements securely in position and metal plates having oval slots formed in their longitudinal centers secured on the top and bottom edges of said level-

body, substantially as and for the purpose set forth.

JOHN BARTHA.
